UNITED STATES PATENT OFFICE

CHARLES D. ROGERS, OF PROVIDENCE, RHODE ISLAND, ASSIGNOR TO THE AMERICAN SCREW COMPANY, OF SAME PLACE.

MACHINE FOR ROLLING SCREW-THREADS.

SPECIFICATION forming part of Letters Patent No. 389,170, dated September 4, 1888.

Application filed May 18, 1888. Serial No. 274,277. (No model.)

To all whom it may concern:

Be it known that J. CHARLES D. ROGERS, a citizen of the United States, residing at Providence, in the county of Providence and State 5 of Rhode Island, have invented certain new and useful Improvements in Machines for Rolling Screw-Threads; and I do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 My improvements herewith relate to the construction of straight dies having ribbed faces placed opposite each other, so as to roll the blank between them in a machine which imparts a reciprocal motion to one of such dies, 20 while the other remains stationary and acts as a back-rest, or in a modification of such machine which imparts a reciprocal motion to both dies in opposite directions, one of such dies only being employed to form the thread, 25 while the other acts as a back-rest or guide.

Some of the machines for rolling screw-threads heretofore in use roll the blank between two cylindrical dies rotating in the same direction, as in the patent to John Sheldon, 30 No. 315,349, dated April 7, 1885, in which case guiding devices are required to retain the blank in proper relation to the dies. Other machines employ pairs of straight dies facing each other, both acting upon the blank to form 35 the thread, as in my United States Patent No. 370,353, of September 20, 1887, in which case any minute disarrangement of the reciprocating mechanism or lack of adjustment between the two dies in the pair may produce a distorted thread. Other machines employ a rotating cylindrical die to form the thread, using a hollow cylindrical die placed outside and around the acting one as a rest to the blank, as 40 in the patent to Clark and Harvey, No. 306,132, dated October 7, 1884. In this form of construction a transverse section of the inner surface of the stationary die forms a larger circle than the periphery of the acting die, and the blank in being rolled between these two surfaces 45 of unequal length is liable to be twisted and distorted, or the metal is plowed along by

the die in the direction of the spiral groove and ultimately squeezed out at the point, thereby producing imperfect screw-threads. These defects in previous machines are avoided by the combined use of straight acting and guiding dies, where the ribs of each die have the peculiar relation to the ribs of the other which I have adopted. 55

The accompanying drawings, representing a machine for rolling threads upon wood-screws embodying my improvements, are as follows:

Figure 1 represents a plan view of a machine having both dies mounted to travel back and forth. Fig. 2 is a plan view of a machine 65 in which one die travels back and forth and the other is stationary. Fig. 3 is a transverse sectional view taken on line *x* *x* of Fig. 2 when the dies are opposite each other. Fig. 4 is a front view, enlarged, of the acting-die. Fig. 70 5 is a cross-sectional view of both dies, the acting die being cut at the line *x* *x*. Fig. 6 is a similar sectional view taken on line *O* *O*. Fig. 7 is a cross-sectional view taken on line *W* *W*, and Fig. 8 is an enlarged sectional view 75 showing the relative arrangement of the thread-forming ribs and the ribs of the back-rest die.

The frame *A* of the machine may be of any convenient form to support the dies and mechanism for producing a reciprocating motion of one or both of them. Such mechanism is well known and may be varied as desired. In the machine shown in the drawings the shaft *S*, by means of the crank *b* and the connecting-rod *C*, moves the cross-head *m* back and forward. The threading-die *B*, being firmly bolted to the cross-head, Fig. 1, represents these reciprocal parts in duplicate, the dies *B* and *B'* both being movable. 80 85

The blank *h* is fed through the inclined ways *m*, and, entering the space between the ends of the dies, as represented in Figs. 1 and 2, is rolled between them, and by the pressure of the ribs of the acting-die *B* the thread is 90 95 formed upon the blank, which is held in position by the back-rest *B'*.

The peculiarity of the straight dies which I use is shown in Figs. 4, 5, 6, 7, and 8. The face of the acting die *B* is provided with a series of inclined parallel ribs, *o*, which have a *V* shape at the beginning (see Fig. 5) and for portions 100

of their length, and are then transformed into ridges, having the cross-section of truncated wedges gradually increasing in breadth upon the face to the end. The die B', whether arranged, as in Fig. 1, to move, or, as in Fig. 2, to remain stationary, is provided with a series of inclined parallel ribs upon its face similar, but reversely inclined, to those upon the face of the acting die B. These ribs for a portion of their length are also V-shaped in cross-section, and are then transformed into ridges whose cross-sections are truncated wedges having faces progressively increasing in width to the end of the die; but the sides of the ribs upon this die are less inclined relatively to each other than the side walls of the corresponding ribs upon the acting die B, for the purpose and with the effect of preventing the sides of the ribs upon the die B' from acting upon the metal of the blank to form the thread, which is shaped by the action of the die B only, thus restricting the function of the die B' to acting as a rest only. This feature of the die is shown exaggerated in Fig. 8.

25 I claim as my invention—

1. In a machine for rolling threads on screw-blanks, a straight die having formed upon its acting face a series of inclined parallel ribs, which for portions of their length are V-shaped in cross section, and are then transformed into

ridges whose cross-sections are truncated wedges having faces progressively increasing in width from the point where they commence to take the truncated form to the end of the ribs, in combination with a straight back rest or die having upon its face a series of inclined parallel ribs similar in form to the series of reversely-inclined parallel ribs upon the acting die, but of less area in cross-section, and thereby adapted to bear only upon the core of a screw-blank rolled between it and the acting die, as described. 35

2. In a machine for rolling screw-threads on screw-blanks, a straight die, substantially as described, in combination with a straight back-rest having formed upon its face a series of inclined parallel ribs, which are similar to the series of reversely-inclined parallel ribs formed upon the acting die, excepting that the sides of the ribs which constitute the walls of the recesses between the ribs upon the back-rest are less inclined relatively to each other than the sides of the corresponding portions of the ribs of the acting die. 40

In testimony whereof I have affixed my signature in presence of two witnesses. 55

CHARLES D. ROGERS.
